BRACKET FOR LIFESAVING EQUIPMENT

Theodore Ziaylek, Jr., Yardley, Pa., assignor to
Ziamatic Corp., Yardley, Pa.

Filed May 3, 1974, Ser. No. 466,698

Term of patent 14 years

Int. Cl. D6—04

U.S. Cl. D8—247

FIG. 1 is a perspective view illustrating a bracket for lifesaving equipment embodying my new design;

FIG. 2 is a top plan view of the equipment illustrated in FIG. 1;

FIG. 3 is a side elevational view of the equipment illustrated in FIG. 1;

FIG. 4 is a front elevational view of the equipment illustrated in FIG. 1;

FIG. 5 is a rear elevational view of the equipment illustrated in FIG. 1; and

FIG. 6 is a bottom view of the equipment illustrated in FIG. 1.

I claim:

The ornamental design for a bracket for lifesaving equipment, as shown and described.
